UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

ELECTRIC SWITCH.

1,285,349.

Specification of Letters Patent. Patented Nov. 19, 1918.

Application filed November 12, 1914. Serial No. 871,748.

To all whom it may concern:

Be it known that I, HENRY T. PAISTE, a citizen of the United States, residing in Philadelphia, Pennsylvania, have invented 5 certain improvements in Electric Switches, of which the following is a specification.

One object of my invention is to provide a novel form of electric switch particularly designed for use in pull sockets, which shall 10 have its parts so constructed as to have a relatively wide break between its contacts when these are separated to open the switch, while having a considerably smaller distance between said contacts just before they are 15 engaged to complete a circuit;—the arrangements of parts being such that the friction between the movable contact or contacts and the coöperating parts shall be relatively small.

20 Another object of the invention is to provide a rotary switch of the pawl and ratchet type, with its parts so arranged and proportioned that its movable contact on breaking the circuit is caused to move through a considerably greater distance than is permitted 25 or necessary in completing said circuit, with a view to rendering said switch available for use in breaking currents of higher voltage than that hitherto considered safe in 30 switches of the same type and general dimensions.

These objects and other advantageous ends I secure as hereinafter set forth, reference being had to the accompanying drawings in which;—

Figures 1 and 2 are respectively a side elevation and a plan of a socket switch showing my invention as applied thereto, the enclosing shell or casing being omitted;

40 Fig. 3 is a plan of the interior of the socket base, the top and certain of the switch operating mechanism being omitted;

Fig. 4 is a detached perspective view of the switch mechanism constituting my invention;

Figs. 5 and 6 are plans of the opposite sides of the chain receiving segment;

Figs. 7 and 8 are plans of the opposite sides of the operating ratchet plate, and

50 Fig. 9 is a diagrammatic development illustrating on a large scale the construction of my improved switch.

In the above drawings 1 represents the usual threaded shell, 2 the porcelain base 55 and 3 the porcelain top of an ordinary pull

socket. Fixed to and rigidly connecting the blocks 2 and 3 is a metallic piece 4 having a tubular flared outlet 5 for the reception and guidance of a chain 6 whereby the switch mounted between said parts is operated. The conductor terminals of the socket are provided by two metallic supports 7 and 8 each having a binding screw and extending between, though not necessarily connected to the insulating blocks 2 and 3, and of these terminals, the first is electrically connected to the spring contact 9 which is centrally mounted in the shell 1 while the second is electrically connected to the contact plate 10 constituting one of the 60 fixed contacts of the switch. The second of the fixed contacts is provided by a similar contact plate 11 electrically connected through a screw 12 with the threaded shell 1.

The two fixed contacts 10 and 11 have the 75 form of helically curved, segmental strips mounted concentrically of the base piece 2 upon oppositely placed helically curved surfaces of what may be described the ratchet teeth of the switch. These plates supporting 80 surfaces are of 90° angular extent and between them are two similar helical surfaces 13 and 14 formed of insulating material of the base 2. It is to be noted however that the vertical faces between the highest portion 85 of the contact strips 10 and 11 and the lowest portions of the surfaces 13 and 14, are of considerably greater length than are the vertical or tooth faces between the highest portion of said surfaces 13 and 14 and 90 the lowest portion of said contacts 10 and 11. This is well shown in Fig. 9 and while I do not wish to be confined to any particular proportion of parts, I have found that one set of said vertical surfaces may be four 95 times as high as the other.

The movable member of the switch consists of a disk 15 of insulating material, such as fiber, to which is fixed a centrally perforated metallic plate 16 having spring 100 contact arms 17 projecting from opposite sides, and helically curved to be concentric with the central opening 18 on said plate. Moreover the curved portions of these arms 17 are inclined to the plane of the disk 15 105 and are designed to coöperate with the contact plates 10 and 11 and the insulating surfaces 13 and 14 carried by the base 2 of the socket.

Between the projecting radial portions of 110

the two arms 17 and in the present instance 90° distant therefrom, is a second pair of oppositely extending arms 19, and the disk 15 with said plate 16 is rotatably mounted 5 on a fixed spindle or post 20 extending centrally between the top 3 and the base 2. This spindle is provided with a square head fitting into a correspondingly formed recess in the top 3 and has mounted upon it a coil 10 spring 21 whose upper end is held from rotation in any suitable manner, as by being extended into a hollow or passage in said head. Its opposite end is hooked into a lug 23 on the chain receiving segment 22, which 15 is likewise rotatably mounted on the spindle and has its body preferably made of insulating material. The periphery of said body carries a circularly curved channel portion 24 designed for the reception of the inner 20 end of the operating chain 6, while at its central portion it carries a metallic plate 25 having four projecting teeth 26 placed to cooperate with the edges of the four arms 17—17 and 19—19 carried by the plate 15.

25 With the above described construction of parts, a succession of outward pulls on the chain 6 will cause the intermittent rotation of the fiber plate 15 with its contact arms 17 through angles of 90°, so that the curved 30 portions of said arms will successively engage the fixed contacts 10 and 11 and the insulated surfaces 13 and 14. When they engage the said fixed contacts the circuit through the socket is closed, since current is 35 free to flow from the terminal 8 to the fixed contact 10; thence through one of the arms 17 to the plate 16, the second arm 17, fixed contact 11, and through the screw 12 to the threaded shell 1. It is noted, however, that 40 if the helical contact portions of the arms 17 are in engagement with the insulating surfaces 13 and 14 when the chain is pulled outwardly, the teeth 26 of the segment 22 engage the edges of the arms 17 and 19 of 45 the plate 15 causing said plate to make a 90° revolution. As a consequence the curved ends of the arms 17 ascend the inclined surfaces 13 and 14, so that both plate 15 and the segment 22 are moved bodily toward 50 the top block 3 of the socket, until finally the ends of said arms pass off of the top edges of said insulating surface and under the action of the spring 21 drop respectively 55 into engagement with the fixed contact strips 10 and 11. This final movement necessary to complete the switch circuit, is relatively short since there is no necessity or advantage for having it of any length and the vertical tooth faces 30 are therefore 60 made comparatively low.

65 A relaxation of the pull on the chain 6 permits the spring 21 to rotate the segment 22 through an angle of 90° while the plate 15 with its arms is held from movement, and

causes the contact arms 17 to slide upwardly on the fixed contacts 10 and 11, thus causing the plate 15 and the segment 22 to move farther toward the top 3 against the action of the spring 21. Finally, however, the 70 ends of the contact arms 17 break the switch circuit by passing off of the top edges of the fixed contact strips 10 and 11, whereupon said arms with the plate 15 and the segment 22 move bodily toward the socket 75 base 2 through a relatively great space, equal to the distance from the highest point of one of the contact plates 10 to the lowest point of the insulating surfaces 13 or 14. In practice the spring 21 is of such design 80 that its action, aided by the resiliency of the arms 17, causes breakage of the circuit to occur very suddenly and this action, supplemented by the wide break caused by the drop of the contact arms 17 onto the insulating surfaces 13 and 14, effectually opens even a comparatively high voltage circuit 85 without permitting the formation of objectionable arcs.

90 From the foregoing description it will be noted that the movement of the contact arms 17 to a height or position from which they can be suddenly moved to give a maximum break, is divided into two portions, so that the inclination of each of the helical surfaces upon which each contact moves is but little more than half that otherwise necessary to secure the wide break between the fixed and movable contacts. As will be understood by those skilled in the art, a large 95 gap is required between the contacts at the time they are separated, while when they are being brought into contact the gap between them may be relatively small. For this reason, the vertical height of the surfaces 30, between the top edges of the insulating surfaces 13 and 14 and the bottom 100 ends of the fixed contacts 10 and 11 may be relatively short, while by reason of the arrangement of parts above described, it is 105 possible to make the vertical height of the surfaces 31, between the top edges of the fixed contact strips 10 and 11 and the lowest 110 portions of the insulating surfaces 13 and 14, much greater than has hitherto been 115 considered attainable under commercial conditions.

I claim:

1. The combination in a pull socket of two blocks of insulating material spaced 120 apart; a pair of conductor terminals; a pair of terminals for an electro-receptive device; and means for electrically connecting the terminals of one pair with those of the other pair respectively, including an electric switch mounted between said blocks, said switch consisting of a series of helical teeth formed in the face of one of said blocks and having between them alternating high and low abutments; fixed contact 125

strips mounted on those teeth having the high abutments; a rotary contact member having inclined spring contact portions formed to slidably engage the contact strips and the helical surfaces of the teeth portions between them alternately when said member is turned; with means for rotating the contact member at will.

2. The combination in a pull socket of 10 terminals; means for electrically connecting said terminals including an electric switch consisting of a series of alternating high and low inclined teeth of insulating material; fixed contact strips mounted on the 15 inclined surfaces of the higher teeth; a rotary contact member having at least one contact portion formed to slidably engage the contact strips on the higher teeth and the inclined surfaces of the lower teeth between them alternately when said member is turned; with means for rotating the contact member at will.
- 20 3. The combination in a pull socket of

two blocks of insulating material spaced apart; a conductor terminal; a terminal for 25 an electroreceptive device; and means for electrically connecting said terminals including an electric switch mounted between said blocks, said switch consisting of a series of alternating high and low teeth on the 30 face of one of the blocks, fixed contact strips mounted on the inclined surfaces of the higher teeth, a rotary contact member having at least one contact portion formed to slidably engage the contact strips of the 35 higher teeth and the inclined surfaces of the lower teeth between them alternately when said member is turned; with means for rotating the contact member at will.

In testimony whereof, I have signed my 40 name to this specification, in the presence of two subscribing witnesses.

HENRY T. PAISTE.
